UNITED STATES PATENT OFFICE.

ZENO LITTMAN, OF NEW YORK, N. Y., ASSIGNOR TO COHOES ENVELOPE CO. INC., OF NEW YORK, N. Y.

PAPER BAG.

Application filed June 9, 1922. Serial No. 567,002.

To all whom it may concern:

Be it known that I, ZENO LITTMAN, a citizen of the United States, residing at New York, in the county of New York and State of New York, have invented certain new and useful Improvements in Paper Bags, of which the following is a specification.

This invention relates generally to containers or envelopes of the type in which flap closure members are employed and particularly relates to the construction of improved closure means.

The general objects of the invention are to provide envelopes or containers of the type referred to in which the security of the closing or sealing means is greatly increased over the security afforded by sealing devices heretofore employed, and in which the closure means can be opened with the greatest ease to provide access to the contents of the container.

In the particular disclosure of the invention made herein I show and describe an envelope of the general type used in mailing photographs, pamphlets and the like, the envelope being provided with a double flap closure construction so arranged that one flap forms an extension of one of the walls of the envelope while the other flap is attached to the inner surface of the other wall along a line spaced from the adjacent end of the wall. This arrangement provides for the folding of the second flap over the contents of the container and also the folding of the first flap over the second flap and into the pocket formed between the second flap and the wall to which it is attached. It will be seen that this structural arrangement provides a double closure which effectually prevents the accidental removal of the contents of the envelope.

I provide also for facilitating the withdrawal of the flaps from closed to open position by the provision of suitable tabs which can be readily seized between the fingers to pull out the tabs from their closed position.

In the drawings,

Figure 1 is a view in front elevation of an envelope embodying the invention.

Figure 2 is a sectional view on an enlarged scale of the upper end of the envelope shown in Figure 1 with two closure flaps shown in open position.

Figure 3 is a view similar to Figure 2 showing one of the flap members folded into closed position.

Figure 4 is a view similar to Figure 3 showing both flap members in folded position.

Figures 5, 6 and 7 are views corresponding to Figures 2, 3 and 4, respectively and showing the provision of finger tabs for use in withdrawing the flap members from closed position.

Referring to the drawings in Figure 1 there is shown an envelope 5 of a suitable type in which to mail photographs, pamphlets and other articles which it is not desired to seal against inspection at the cost of first-class postage. In order to provide a closure which will satisfy the postal regulations relating to ready inspection and at the same time provide a secure closure which will prevent the accidental removal of the contents of the envelope in transit through the mails, I make use of two closure flaps 6 and 7 which can be utilized to provide a double closure for the open end of the envelope.

The closure flap 6 forms a simple extension of the rear wall 8 of the envelope 5 while the other flap 7 may be formed integrally with or attached to the forward wall 9 of the envelope in such manner as to form a pocket 10 between the wall and the outer face of the flap. Preferably the depth of the pocket 10 is substantially the same as the extension of the rear closure flap 6 from the end of the wall 8. The closure flap 7 may be attached to the end of the envelope wall 9 at 11 and pasted to the wall as a reinforcement thereof as indicated in Figure 2 of the drawing, or attached to the wall at the point 12 to form the closed end of the pocket 10. It will be clear that if the flap 7 is integral with the wall 9 it will be folded back on the wall at the point 11.

With the structural arrangement disclosed, and referring to Figure 3, the forward closure flap 7 in closing the envelope is first folded over the envelope contents 13 as indicated. This is followed by the folding of the rear flap 6 over flap 7 and into the pocket 10 as indicated in Figure 4. This completes the closing operation and the contents 13 of the envelope are held in place by a double set of closure flaps as will be apparent.

Referring to Figures 5, 6 and 7 of the drawings, finger tabs 14 and 15 are attached to the closure flaps 6 and 7 or are formed integrally therewith. The tabs 14 and 15 form convenient members for facilitating the opening of the closure flaps. In Figure 6 of the drawing it will be seen that the end of the tab 14 occupies a position where it can be readily grasped between the fingers to provide for the withdrawal of the flap 7. In like manner the tab 15 occupies a position when the second flap 6 is folded as in Figure 7 where the tab 15 can be readily grasped to withdraw the flap 6. It will be clear that in the order of removal tab 15 and flap 6 are first withdrawn, followed by the withdrawal of tab 14 and flap 7 to open position when the contents of the envelope can be readily inspected or removed.

20 What I claim is:

1. In an envelope, a closure flap forming an extension of one wall of the envelope, and a second closure flap member attached to the inner surface of the other wall at the end 25 thereof and folded back along said wall for a distance substantially equalling the extension of the other flap beyond the end of the wall, said second closure member being folded back on itself at and extending inwardly 30 from the open end of the envelope to a distance substantially equal to the projection of the other flap member.

35 2. In an envelope, a closure flap forming

an extension of one wall of the envelope, a closure flap attached to the inner surface of the other wall at a point spaced from the adjacent end of the wall, and extending substantially to the free end of the first-named flap, and a finger tab carried by one of said closure flaps in position to be grasped when 40 the closure flap is in closed position.

3. In an envelope, a closure flap forming an extension of one wall of the envelope, a closure flap attached to the inner surface of the other wall in such manner as to form a 45 pocket in which to receive the first-named closure flap, said closure flap extending substantially to the free end of the first-named flap, and a finger tab member carried by each of said closure flaps in position to be grasped 50 when the closure flaps are in closed position.

4. In an envelope, a closure flap forming an extension of one wall of the envelope, a closure flap attached to the inner surface of the other wall in such manner as to reinforce 55 the wall and form a pocket in which to receive the first-named closure flap, said closure flap extending substantially to the free end of the first-named flap, and a finger tab attached to the rear surface of each of the 60 flaps in such manner that the one end of each tab is accessible when the corresponding flap is in folded condition.

In testimony whereof I affix my signature.

ZENO LITTMAN.
